SPORTS COVERALL FOR SNOW ENVIRONMENT

Donald P. Ferguson, Rte. 2, Wirt, Minn. 56688

Filed Sept. 21, 1971, Ser. No. 182,571

Term of patent 14 years

Int. Cl. D2—02

U.S. Cl. D2—31

FIG. 1.

FIG. 2.

FIG. 3.

FIG. 4.

FIG. 1 is a front perspective view of a sports coverall for snow environment with the hood down showing my new design;

FIG. 2 is a rear perspective view of the garment with the hood down;

FIG. 3 is a front perspective view showing the garment hood up and the rear flap down; and

FIG. 4 is a rear perspective view of the garment with the hood up and the rear flap opened and down.

The characteristic feature of my design resides in the configuration of the drop seat portion of the sports coverall for snow environment all as shown on the drawing.

I claim:

The ornamental design for a sports coverall for snow environment, as shown and described.
